(57) **CLAIM**

The ornamental design for a shelf-ready packaging for food products, as shown and described.

DESCRIPTION

FIG. 1 is an exploded perspective view of the shelf-ready packaging for food products shown in a position of use with an unclaimed lid and food products drawn in broken lines for environment purposes.

FIG. 2 is a front, right, and top perspective view thereof.

FIG. 3 is a front view thereof, the rear view being an identical image.

FIG. 4 is a right side view thereof, the left side view being a mirror image.

FIG. 5 is a top view thereof; and,

FIG. 6 is a bottom view thereof.

The dash-dot lines shown in the drawings are for environmental purposes only and form no part of the claimed design. The dash lines shown are perforations in the design and are a part of the claimed design.
